UNITED STATES PATENT OFFICE.

WILLIAM C. BROWN, OF SPRINGFIELD, MASSACHUSETTS.

CLAMP FOR SADDLE-POSTS.

SPECIFICATION forming part of Letters Patent No. 630,176 dated August 1, 1899.

Application filed June 14, 1899. Serial No. 720,447. (No model.)

To all whom it may concern:

Be it known that I, WILLIAM C. BROWN, a citizen of the United States of America, and a resident of Springfield, in the county of Hampden and State of Massachusetts, have invented 5 certain new and useful Improvements in Clamps for Saddle-Posts, of which the following is a full, clear, and exact description.

This invention relates to improvements in 10 clamping devices for confining the post of the saddle or seat support in the socket therefor in the tubular frame or for confining the stem of the handle-bar in the tubular head of a bicycle-frame.

15 The invention particularly relates to that known class of clamp for the purpose designated which comprises a sleeve or thimble which is contractible about the post, the bushing outside the sleeve, the sleeve and thimble being relatively formed with inclined surfaces, whereby the movement of the one endwise in relation to the other insures the contraction of the sleeve about the post, and an 20 operating-nut engaging one of said parts for imparting the endwise movement thereof in relation to the other.

25 The object of the present invention is to provide a confining device of the class indicated which is simpler than those heretofore proposed and one that is most efficient and certain in its confining effect and generally more advantageous and desirable.

The invention consists in the construction and combination or arrangement of the parts 30 comprised in the post-clamp, all substantially as hereinafter fully described, and specifically set forth in the claim.

Reference is to be had to the accompanying drawings, in which the improved post-clamp 35 is illustrated, and in which—

Figure 1 is a vertical sectional view through the portion of the frame of a bicycle comprised at the junction of the upright central member and the top bar and the rear downwardly-extending frame member and through 40 the clamping device, which is shown in confinement about the post of the saddle-support. Fig. 2 is a side view of the inner sleeve. Fig. 3 is a cross-section of the same, taken on 45 the line $x-x$, Fig. 2. Fig. 4 is a side view, partly in section, of the bushing which sur-

rounds the sleeve; and Fig. 5 is a cross-section of the same on line $y-y$, Fig. 4.

Similar characters of reference indicate corresponding parts in all of the views. 55

In the drawings, A represents the part of the bicycle-frame which comprises the approximately upright member a , having the upwardly-opening socket b .

B represents the post of the saddle or seat support. 60

The improved clamping device consists of the sleeve C, the bushing D, and the nut G of a particular construction and arrangement the one relatively to the other, as will be now 65 set forth.

The sleeve C is internally of cylindrical form to conform to the post B, and at its upper end it is provided with the external flange or annular bead or projection d , and said 70 sleeve is externally downwardly tapered, as indicated at f . The sleeve is provided with one slit or kerf h , which extends from end to end thereof, and is provided, furthermore, with one or more slits or kerfs i , which extend 75 from its upper end downwardly suitably near to its lower end.

The nut G is provided internally within its upper portion with the annular groove j , into engagement with which the external annular 80 projection d of the sleeve may be brought, the latter being contracted therefor, as permitted by the kerfs through its circular wall. The portion of the nut below the groove j is 85 internally screw-threaded, as indicated at m .

The external diameter of the sleeve is somewhat less than the internal diameter of the threaded portion of the nut, although the external diameter of the flange exceeds the internal diameter of such threaded portion of 90 the nut, and hence while the sleeve-flange is engaged in the nut-groove, so that the nut may be turned relatively to the sleeve, there is an annular space below the flange between the threaded portion of the nut and the sleeve 95 therewithin, into which is entered for screw engagement the externally-screw-threaded upper end portion m of the tubular bushing D. The bushing externally is of a size to conform to the circular wall of the socket b , 100 and it is provided with the tapered internal surface indicated at o , which may be more or

less abrupt or gradual, as preferred. The bushing is provided with one or more slots or kerfs q , extending from its lower end nearly to its upper end.

- 5 By turning the nut, the lower end of which is usually seated upon the upper end of the tubular or socketed frame member a , the bushing D is caused to have an endwise movement as its threaded upper end is drawn 10 farther upwardly within the nut, and the internal side of the downwardly-widening wall of said bushing crowding against the outer side of the downwardly-tapered sleeve not only contracts the sleeve most firmly against 15 the post, but the bushing is, on the other hand, crowded for a hard bind against the internal wall of the socket a , within which the clamp is applied.

While I am aware that various constructions of clamps for seat-posts and handle-bar stems have been proposed comprising in some manner the combination of a sleeve, bushing, and nut, and while I do not wish to be understood as claiming a clamp having such components, broadly considered, I have in the device shown provided a very superior clamp and one of advantage by reason of its simplicity, directness of action, and especially because of the construction and arrangement 25 of the nut with the groove therewithin above its threaded portion and assembled in relation to the flange-topped sleeve, so that the annular space is left below the flange for the introduction of the threaded upper end of 30

the bushing, the threads of which are entirely 35 inclosed, concealed, and protected from dirt and from being jammed.

The only portion of the clamp that is exposed is the nut, which is naturally of an ornamental and slight appearance. 40

Having thus described my invention, what I claim, and desire to secure by Letters Patent, is—

In a clamp for a seat-post or other similar part of a bicycle, the combination with the 45 nut having within its upper portion the annular groove, and internally threaded therebelow, of the contractile sleeve provided at its upper end with the external projection adapted to be engaged in the internal groove 50 of the nut, being therebelow of a diameter less than the threaded internal portion of the nut, and being externally downwardly tapered, and the contractile and expansible bushing, having its wall widening downwardly, surrounding the sleeve, and having its upper extremity externally threaded and entered within the annular space between the threaded portion of the nut and the sleeve, and screw-engaged with said threaded portion, substantially as and for the purposes set forth. 55

Signed by me, at Springfield, Massachusetts, this 12th day of June, 1899.

WILLIAM C. BROWN.
